WIRELESS AERIAL

Norman Maxwell Best, London, England, assignor
to Antiference Limited, London, England, a
British company

Application April 4, 1950, Serial No. 153,905
In Great Britain May 6, 1949

9 Claims. (Cl. 250—33.51)

1

The present invention relates to an improved aerial such as may be used, for example, for the transmission or reception of wireless waves, and although not limited exclusively thereto, is particularly useful for the reception of television signals.

A known form of aerial at present commonly in use for the reception of television signals, comprises a pair of aerial rods constituting a dipole and a pair of parasitic rods, the latter pair serving as either a director or reflector for the dipole.

When designed for such a known reception of horizontally plane polarised waves, the dipole comprises two similar, horizontal, colinear, spaced, electrically conductive rods having their adjacent ends gripped in an insulating junction box which is held at one end of a hollow horizontal supporting arm. The parasitic element, for example a reflector, may be a single rod or tube or may comprise a pair of similar, horizontal, colinear, electrically conductive rods having their adjacent ends connected together and gripped in a junction box held at the other end of the supporting arm.

The dipole, reflector and supporting arm are arranged in H-formation all in the same horizontal plane.

A pair of insulated leads, such as a concentric or twin cable, run from the adjacent ends of the dipole rods to the set.

Such a known aerial is illustrated diagrammatically and in plane view in the accompanying Figure 1, the dipole rods (D) being shown at 20, 21, the parasitic rod or rods (P) at 22, 23, and the supporting cross-arm at 24.

The polar diagram in a vertical plane of such a known H-aerial is shown in Figure 2, it being assumed that the waves received are polarised in the horizontal plane of Figure 1.

It will be seen that such an aerial has maximum sensitivity on the dipole side of the aerial and minimum sensitivity on the reflector side.

It is an object of the present invention to provide an aerial which although of receptivity comparable with, or better than, known aerials, yet is cheaper to manufacture. Another object is to provide an aerial of higher selectivity than those now commonly in use for the reception of television signals, without increasing the cost of manufacture or decreasing the signal strength receivable by the aerial.

Preferred forms of the invention will now be described with reference to the accompanying drawing, in which

2

Figure 1 shows the known form of aerial described above.

Figure 2 is its polar diagram in a horizontal plane.

Figure 3 is a plan of one form of aerial, constructed and arranged to operate in accordance with this invention.

Figure 4 is the polar diagram given by the aerial of Figure 1.

Figures 5 and 6 are respectively a plan and elevation, on a more open scale, of the aerial shown in Figure 3.

Figure 7 is a perspective view, on a yet more open scale, of the junction box shown in Figures 5 and 6, and

Figures 8 to 11 inclusive are plan views of various aerials, all of which are modifications of the aerial of Figure 3, and all lying within the scope of the present invention.

The aerial illustrated in Figures 3, 5, 6 and 7 comprises a dipole D and parasitic member P in the form of two dipole rods 25, 26 and two parasitic rods 27, 28, arranged to extend radially in a horizontal plane, from an approximately common centre at equiangular spacings of 90°.

The four rods are gripped at their inner ends in an insulating junction box 29 formed with four sockets for this purpose.

The junction box is mounted in a bent hollow bracket 30 which is secured to a hollow mast 31 (Figure 5 only).

The two dipole rods 25, 26 are spaced at their inner ends and are respectively connected to terminals 32 and 33, whence run insulated cables to the set. As shown the insulated cables are concentric, the centre core 34 of the cable being connected to rod 25 via terminal 32 and an intermediate conductor 35 of the cable being connected to rod 26 via terminal 33.

The parasitic rods 27 and 28 are connected together by a yoke 36.

Twin cables may be used in place of the concentric ones shown.

When such an aerial is used to receive wireless waves polarised in a horizontal plane, the rods are mounted so as to lie in a horizontal plane and the horizontal polar diagram given by one such aerial is shown in Figure 4. It will be seen that the curve is of cardiac shape roughly similar to that of Figure 2 but displaced by 180° with respect thereto. Maximum sensitivity is thus given when the parasitic rods point towards the source and not, as in the case of the known H-aerial, when the dipole rods point towards the source.

The polar diagram of Figure 4 applies when

the dipole rods are longer than the parasitic rods and totally different diagrams are obtained when the lengths of the dipole and parasitic members are altered.

It will be seen that in the arrangement of Figures 3 to 7 the parasitic member is operating as a director. With such an aerial, and for the reception of waves of 45 megacycles, the length of each dipole rod may be about 5' 9" and of each director rod about 5' 3". The front to 10 back sensitivity ratio is then about 12/1.

With dipole rods 5' 3" and parasitic rods 5' 9" the latter act as a reflector and the polar diagram is reversed. The front to back ratio is with this arrangement about 1.5/1.

With an aerial of this kind only one junction box is required and no supporting cross-arm is necessary.

Since its polar diagram is non-circular, i. e., it has selective sensitivity, it is preferably arranged with the direction of maximum sensitivity pointing towards the source, if there is no appreciable interference to be taken into account.

If, however, there is a source or sources of interference to be taken into consideration, then a compromise position is adopted with the source of interference as near as possible on the direction of minimum signal strength and the source to be received on the direction of maximum signal strength, but as the relative strengths of the two sources affect the final position the latter would usually be arrived at by trial and error.

In Figure 8 is shown an aerial similar in all respects to that of Figures 3 to 7 except that the parasitic rods 38 and 39 are connected to one of the dipole rods, namely, the lower rod 40.

The advantage of a known folded dipole or of a known double V-shaped dipole may be applied to the novel aerial described above with reference to Figures 3 to 7.

Thus, as shown in Figure 9, the parasitic rods 41 and 42 remain unchanged whilst the rods 25 and 26 of Figure 3 have been replaced by a pair of folded, but inclined, rods 43 and 44.

In the arrangement of Figure 10 both the dipole rods, 45 and 46, and the parasitic rods, 47 and 48, are folded.

In Figure 11 the dipole rods 25 and 26 of Figure 3 are each replaced by a pair of V-shaped rods 49 or 50 respectively. If desired, both the dipole and parasitic rods may each be replaced by a pair of V-shaped rods.

The modifications described with reference to Figures 8 to 11 as a general rule do not give as high sensitivity as the arrangement of Figures 3 to 7, but in some respects have better polar diagrams, so that they may be used with advantage in special circumstances.

The word rod as used herein is intended to cover tube-like as well as rod-like members.

Wide variations of the properties of all such aerials can be made by varying the lengths of the rods and the angles between them and by placing the rods out of a common plane.

Good reception can be obtained by placing the rods in a common plane parallel to the plane of polarisation of the waves to be received, and at 90° angular intervals about the common 70 centre.

It has been found, however, that the angle α (Figure 3) between the dipole rods or the angle β between the parasitic rods, may be between 60° and 120° without seriously affecting reception, and that the rods can be placed out of the plane of polarisation without serious diminution of the signal strength.

What I claim is:

1. An aerial comprising four rods extending radially from a common centre, two being electrically insulated from each other at their inner ends, and the other two being in electric connection at their inner ends.

15 2. An aerial comprising four rods supported so that they lie in a common plane and extend radially from a common centre, two of the rods being electrically insulated from each other and the other two being electrically connected together.

20 3. An aerial comprising a pair of electrically insulated dipole rods inclined obliquely one to the other and a pair of electrically connected parasitic rods also obliquely inclined one to the other, the four rods being supported so that they lie in a common plane and extend radially from a common centre.

25 4. An aerial as claimed in claim 1, wherein the angle between the electrically connected rods lies between 60° and 120°.

5. An aerial as claimed in claim 1, wherein the angle between the electrically insulated rods lies between 60° and 120°.

6. An aerial as claimed in claim 1, wherein the four rods are equiangularly spaced in a common plane.

7. An aerial as claimed in claim 3 wherein the parasitic rods are connected electrically to one of the dipole rods.

8. A wireless aerial comprising four electrically conductive elements mounted so that they extend radially away from a common center in a common flat plane, two adjacent ones being electrically insulated from each other and forming a dipole and the other two being electrically connected and forming parasitic elements.

45 9. A wireless aerial comprising four electrically conductive elements held at their inner ends in a common support so that they extend radially away from the support in a common flat plane, angles between any two adjacent elements being between 60° and 120°, one pair of adjacent elements being electrically insulated from each other so as to constitute a bent dipole and the other pair being electrically connected together so as to form a parasitic element.

NORMAN MAXWELL BEST.
